DIAPHRAGM UNIT FOR LOUD-SPEAKERS

Reginald Denison Charlesworth, Dee Why, New South Wales, Australia, assignor to Magnavox (Australia) Pty. Ltd., East Sydney, New South Wales, Australia, a corporation of Australia

Application August 28, 1948, Serial No. 59,323
In Australia August 27, 1947

2 Claims. (Cl. 179—115.5)

1

This invention relates to improvements in loud speakers of the type in which a diaphragm carries a voice coil that operates in a magnetic air gap, and, in particular, relates to improvements in means and methods for constructing a diaphragm assembly unit that in itself is independent of and contains no portion of the particular magnetic unit to be used, although this diaphragm assembly unit is adapted to co-operate with the magnetic unit or units and particular locking means whereby efficient loud speakers are produced, and has been devised to produce a diaphragm assembly unit that is complete in itself and may be manufactured and used or stored for later use with particular magnetic units and locking members also of independent and individual construction and so that the individual units of a complete loud speaker may be demounted, inspected, cleaned, replaced or interchanged without the use of gauges, jigs, or special or precision equipment. In the following description and claims the words gauge or gauges include and cover jigs and the like.

In the formation of my improved diaphragm assembly unit I provide a diaphragm housing, a diaphragm to be secured to said housing and provided with a voice coil former and voice coil, a locating and supporting spider for said diaphragm and securable to the diaphragm housing and to the diaphragm.

The diaphragm housing may be formed of metal pressed or die cast or other stiff and relatively rigid material such as moulded plastic, and, preferably, in the approximate form of a frustro-cone or the like, open at each end, with windows or similar apertures in its side walls; the larger outer end of this housing is outwardly rimmed or ledged to support the outer edge of the diaphragm to be used.

The housing side walls are formed or provided with an internally extending flat ledge or shelf of any desired width which terminates in a preferably right angled backward extension of any desired shape, length and diameter; the rear end of this extension is formed or provided with a base and this base is provided with an accurately placed aperture of circular, oval, square, rectangular or other desired section. This aperture is adapted to positively co-operate detachably with a magnetic unit of the loud speaker to be formed.

An external outwardly extending flat member may be formed or detachably provided on the outer walls of the housing and, preferably, is secured to the inner flat ledge on the housing side walls.

2

The diaphragm to be mounted concentrically in the diaphragm housing is formed of suitable material, such as paper, and is, preferably, of frustro-conical, elliptical or the like shape and with an outwardly extending edge on its larger outer end to nest in the outer rim of the housing. The inner or apex end of the diaphragm is provided with a concentric neck and to this neck is concentrically secured, as by common practice, a voice coil former carrying a voice coil which is adapted to project through the housing base aperture.

A spider of any desired material in disc form and, preferably, corrugated, is formed or provided concentrically with a central aperture and with a cylindrical or other shaped neck of any desired length that is adapted to fit snugly about the diaphragm neck; the outer periphery of the spider is adapted to lie on and to be pressure cemented or otherwise secured to the inner flat ledge or shelf on the housing side walls.

To secure the spider so that its central aperture will be concentric with the vertical axis of the diaphragm I employ a spider gauge that has a lower cylindrical or other shaped base nesting a ring on its upper face. This ring fits from the rear exactly into the back open end or aperture in the rear extension of the diaphragm housing; a detachable central boss is fitted on the gauge,

30 in some forms, concentrically with the ring and is of the correct size and shape to fit the neck of the spider. After the spider is positioned on and about this boss the outer peripheral edge of the spider is cemented to the flat ledge on the inner housing walls, and when the cement has set the gauge is removed and replaced by a similar gauge that has a central boss of smaller diameter than that of the spider gauge boss and adapted to fit accurately the voice coil former.

40 In practice, however, the central boss of the spider gauge may be removed and replaced by a smaller diameter central boss so that the gauge now may be used as a voice coil former gauge.

After cement has been applied to the diaphragm outer edge and the diaphragm neck, the diaphragm with voice coil attached is presented to the voice coil gauge and the voice coil former is slid on and about the boss until the larger end of the diaphragm is secured to the housing rim. The spider is also secured to the diaphragm neck. On removal of the gauge the assembled diaphragm unit is ready for use or storage.

55 In a modified method and means for positioning the various members of the diaphragm assembly in correct concentric relation to each other and to the diaphragm housing, the aper-

ture in the housing base may be of any contour and of slightly larger diameter than that of the voice coil to be used; the whole aperture is not necessarily concentric with the said voice coil; the base of the housing is of any desired width and is provided with a series of spaced holes which may be of any desired shape and size and on which gauges or the like may be positioned to align the spider and then the diaphragm and the voice coil in the manner as above described. The said holes are adapted to detachably and positively co-operate with a magnetic unit for the loud speaker to be formed.

In the accompanying drawings which illustrate forms of construction of a diaphragm assembly unit:

Fig. 1 is a rear half plan showing a housing, diaphragm, spider and voice coil and a similar half plan with the housing removed;

Fig. 2 is a half elevation and a half sectional elevation of the construction shown in Fig. 1;

Fig. 3 is a sectional elevation of a spider gauge;

Fig. 4 is a plan of the same;

Fig. 4A is a sectional elevation of a voice coil former boss;

Fig. 4B is a sectional elevation of a modified form of spider gauge;

Fig. 5 is a plan of a diaphragm housing with a modified form of base; and

Fig. 6 is a central sectional elevation of Fig. 5.

A diaphragm housing 10, formed with an outer rim 10A and windows 10B, is formed or provided on its inner side walls with a flat unchannelled ledge or shelf 11 that is provided with slots 11A, preferably arcuate in form, to function as part locking members of means for locking the units of a loud speaker to each other after assembly. The housing is formed or provided with a cylindrical extension 11B on the shelf edge at right angles to shelf 11. The cylindrical extension may be replaced by an extension of any desired cross section. In each case a base 11C of any desired width is formed or provided on the rear end of the extension and is provided with an aperture 11E, in the preferred form concentric with the ledge 11 and illustrated in Figs. 1 and 2 as concentric with the ledge 11 and the outer rim 10A of the housing, and is adapted to detachably co-operate with a magnetic unit without the aid of assembly gauges, jigs or the like, when the individual members of a loud speaker are being assembled. In other forms of construction shown in Figs. 5 and 6 the base is provided with a series of spaced holes 11D of any desired shape and size which holes may detachably co-operate positively with a magnetic unit without the use of gauges, jigs, or the like in the complete and final assembly of a loud speaker.

An outwardly extending flange 11F, shown in Fig. 6 as detachable, is provided with part locking members such as slots 11G. The flange may be integral with the outer walls of the housing 10 adapted to make a close fit on its cylindrical outer portion 13Z in the rear housing aperture 11E, as the base 11C is seated in a portion 50 of the ring 13C.

A frustro-conical or the like diaphragm 12 has on its larger outer end an edge 12A that is to be secured to housing rim 10A. The inner or apex end of the diaphragm is provided with a concentric neck 12B to which is secured in known manner a voice coil former 12C and voice coil 12D that project through the aperture in the housing base.

A corrugated spider 13 is formed or provided

5 with a concentric neck 13A that is adapted to be cemented to the diaphragm neck 12B, and also is provided with a flat peripheral portion 13B adapted to be cemented to the housing inner shelf 11.

6 The spider is positioned on the housing by means of a spider gauge (Fig. 3) that carries on its base plate a ring 13C that is adapted to make a close fit in the rear housing aperture 11E. A removable central boss 14 preferably concentric with ring 13C is adapted to take the spider neck 13A and, when the spider is positioned on the gauge, its periphery 13B is cemented to the shelf 11. The boss 14 is then removed and replaced by a smaller diameter boss 15 (Fig. 4A) adapted to fit closely the voice coil former 12C when the diaphragm is presented to the gauge and housing. Cement is applied to the outer rim of the diaphragm and to the diaphragm neck before the diaphragm is positioned on the gauge.

7 In a modified method and means for correctly assembling the structural members of the diaphragm assembly unit the base 11C of the housing is provided with a series of spaced holes 11D preferably concentric with the inner ledge 11 and the housing rim 10A; the aperture 11E in this base is of any desired contour and of sufficient size and situated to clear the voice coil. As shown in Fig. 4B a gauge similar to that shown in Fig. 3 and having a removable central boss 14 within the ring 13C that is provided with a spaced series of studs 14B that engage positively the holes 11D and so that the boss 14 is in concentric relation to the vertical axis of the housing and fits the neck of the spider 13. The spider is then cemented to the shelf 11. By the use of a substituted voice coil former boss 15 for the boss 14 the voice coil former may be correctly positioned and the spider cemented to the diaphragm neck 12B and the diaphragm to the housing rim 10A.

8 By either of these centring means and methods the vertical axis of the spider, the longitudinal axis of the voice coil former and voice coil and the centre in the housing base are brought into and may be secured in the same straight line which is the vertical axis of the housing and of the diaphragm and that in turn is vertical to the base 11C; and this centring is effected independently of any portion of a magnetic unit to be used with the diaphragm assembly produced as described above.

9 Having now particularly described and ascertained the nature of this said invention, and in what manner the same is to be performed, I declare that what I claim is:

1. In a loud speaker, a diaphragm assembly unit comprising in combination, a diaphragm housing, having a base and being provided with an accurately positioned aperture in its base, a diaphragm, attached to said housing and fitted with a voice coil former, a voice coil carried by said voice coil former, and a locating and supporting spider attached to said diaphragm and to said housing, said housing having an inwardly extending flat ledge on the side wall portions thereof, a right angled extension on the radially inner edge of the ledge, and the said base for the extension containing the aperture which is accurately positioned with relation to the voice coil former, said ledge carrying said spider and having part locking means provided therein, so that the individual parts of the complete diaphragm assembly are in concentric relationship to each other and the voice coil is in correct oper-

ative alignment with the aperture in said base, said flat ledge having a plurality of arcuate slots provided therein to form said part locking means, which slots are concentric with said aperture in said housing.

2. In a loud speaker, a diaphragm assembly unit comprising in combination, a diaphragm housing having a base and being provided with an accurately positioned aperture in its base, a diaphragm attached to said housing and fitted with a voice coil former, a voice coil carried by said voice coil former, and a locating and supporting spider attached to said diaphragm and to said housing, said housing having an inwardly extending flat ledge on the side wall portions thereof, a right angled extension on the radially inner edge of the ledge, and the said base for the extension containing the aperture which is accurately positioned with relation to the voice coil former, so that the individual parts of the 20 complete diaphragm assembly are in concentric relationship to each other and the voice coil is in correct operative alignment with the aperture in said base, and an outwardly extending ledge member secured to said ledge and having part 25 locking means provided therein for engaging a magnetic unit.

REGINALD DENISON CHARLESWORTH.
